(57) **CLAIM**

The ornamental design for a display screen or portion thereof with an animated graphical user interface, as shown and described.

DESCRIPTION

FIG. 1 is a front view of a first image in a sequence of a first embodiment for a display screen or portion thereof with an animated graphical user interface showing the new design;

FIG. 2 is a front view of a second image thereof;

FIG. 3 is a front view of a first image in a sequence of a second embodiment for a display screen or portion thereof with an animated graphical user interface showing the new design;

FIG. 4 is a front view of a second image thereof;

FIG. 5 is a front view of a first image in a sequence of a third embodiment for a display screen or portion thereof with an animated graphical user interface showing the new design;

FIG. 6 is a front view of a second image thereof;

FIG. 7 is a front view of a first image in a sequence of a fourth embodiment for a display screen or portion thereof with an animated graphical user interface showing the new design;

FIG. 8 is a front view of a second image thereof;

FIG. 9 is a front view of a first image in a sequence of a fifth embodiment for a display screen or portion thereof with an animated graphical user interface showing the new design;

FIG. 10 is a front view of a second image thereof;

FIG. 11 is a front view of a first image in a sequence of a sixth embodiment for a display screen or portion thereof with an animated graphical user interface showing the new design; and,

FIG. 12 is a front view of a second image thereof.

The outermost broken line rectangle illustrates a display screen or portion thereof and forms no part of the claimed
